(57) **CLAIM**

The ornamental design for a thread gauge puck, as shown and described.

DESCRIPTION

A portion of the disclosure of this patent document contains material to which a claim for copyright and trademark is made. The copyright and trademark owner has no objection to the reproduction of the patent document or the patent disclosure, as it appears in the U.S. Patent Office records, but reserves all other copyright and trademark rights whatsoever.

FIG. 1 is a perspective view of the thread gauge puck of my new design;

FIG. 2 is a first side view thereof;

FIG. 3 is a second side view thereof;

FIG. 4 is a third side view thereof;

FIG. 5 is a fourth side view thereof;

FIG. 6 is a top view thereof; and,

FIG. 7 is a bottom view thereof.

The portions (including the internal threading) of the thread gauge puck in FIGS. 1-7 shown in broken lines are included to show features that form no part of the claimed design.

1 Claim, 5 Drawing Sheets
